UNITED STATES PATENT OFFICE.

AUGUST H. KATTERJOHN, OF DENVER, COLORADO, ASSIGNOR TO THE DENVER ROCK DRILL MANUFACTURING COMPANY, OF DENVER, COLORADO, A CORPORATION OF DELAWARE.

FLUID-OPERATED TOOL.

Application filed November 3, 1925. Serial No. 66,578.

The present invention relates specifically to tools of the type having a long stroke piston hammer of small diameter, though not necessarily limited thereto.

5 The object is to provide a novel structure of an efficient character for distributing the motive fluid to the piston hammer.

In the accompanying drawings:

Figure 1 is a longitudinal sectional view 10 of one embodiment of the invention, showing the hammer at the delivery end of its power stroke.

Figure 2 is a similar view with the hammer at the rear end of its return stroke.

15 Figures 3 and 4 are detail sectional views on an enlarged scale of the valve mechanism in the positions shown respectively in Figures 1 and 2.

Figure 5 is a detail view of the exterior of 20 a portion of the rear end of the valve.

In the embodiment disclosed a cylinder member 5 is employed, having a piston chamber 6, in which a reciprocatory cylindrical piston 7 is located. This piston 7, in the 25 present embodiment, delivers blows against a tappet 8 that transmits said blows to a suitable tool, a portion of which is shown at 9. The rear end of the cylinder member has an enlarged bore 10, in which is fitted a 30 valve chest 11. Interposed between the front end of this valve chest 11 and the front end wall of the enlarged bore 10 is a washer or front head 12. A rear head 13 is located at the rear end of the chest, and is 35 held in place by the usual rear head 14 having a handle, a portion of which is shown at 15. Motive fluid is supplied from any suitable source, through a coupling 16, the bore of which has communication through a 40 passageway 17 with a chamber 18, formed in the head 14 behind the valve chest head 13.

The valve chest 11 contains a valve chamber, around which is a front internal annular groove 19. Behind this groove is an annular exhaust groove 20, and in rear of said 45 exhaust groove are two other annular grooves 21 and 22. The diameter of the valve chamber is slightly greater than the diameter of the piston chamber 6 and in 50 said valve chamber is located an automatic reciprocatory tubular distributing valve 23. The internal diameter of this valve is the same as that of the piston chamber 6 and in 55 the rear end of the piston hammer 7 is adapted to run into and out of the valve 23,

as will be clear by reference to Figures 2 and 4.

The valve 23 is provided with an outstanding annular flange 24 that operates in the front groove 19 and constitutes a piston 60 for moving the valve 23 rearwardly, as hereinafter explained. Its thickness is therefore less than the width of the groove. The cylinder member 5 has an exhaust port 25 between its ends that is traversed by the piston 65 hammer 7, and opening into the piston chamber 6 in rear of the exhaust port 25 is the inlet end of a passageway 26 that opens through the washer or head 12 into the groove 19 in advance of the piston flange 24. 70 The valve 23 is also provided with one or more transverse ports 27 that open therethrough into the groove 19 in advance of the piston flange 24. This groove 19 furthermore has an exhaust port 28 opening therefrom to atmosphere but the port 28 is of less area or capacity than the combined areas of the passageway 26 and ports 27. A relief port 29 communicates with the rear end of 75 the groove 19 behind the piston flange 24. 80

Supply ports 30, opening through the rear valve chamber head 13 from the chamber 18 have communication with the rearmost annular groove 22 of the valve chest. From the intermediate annular groove 21 a passageway 31 leads to the front end of the piston chamber 6 in advance of the piston hammer 7. The intermediate groove 20 of the valve chest has an exhaust port 32 opening to atmosphere, and the valve has ports 33 that 85 communicate with the groove 20 when said valve is in its rearmost position, and thus afford exhaust means through the port 32 that is supplemental to the exhaust port 25. The rear portion of the valve 23 has an external groove 34 and two milled notches 34^a, the notches and grooves affording communication between the grooves 21 and 22 when the valve is in its rearmost position, and the groove 34 affording communication between 90 grooves 21 and 20 when the valve is in its foremost position. The purpose of the two notches and narrow annular groove on the outside of the valve is to restrict the amount of air going to the front end of the cylinder 100 and also to provide bearing for the rear end of the valve to slide in.

The operation of the apparatus is substantially as follows: Assuming the parts in 105 the position shown in Figures 1 and 3 with 110

the piston hammer at the end of its forward or blow delivering stroke and the valve in its rearmost position, it will be noted that motive fluid from the chamber 18 will pass 5 through the ports 30, channels 22, 34 and 21 to the passageway 31, and thus find its way to the front end of the piston chamber 6, where it will operate against the front end of the piston, causing the latter to move 10 rearwardly. The motive fluid in rear of the piston will exhaust freely through the exhaust port 25 until said port is closed, and thereafter can pass through the passageway 26 and ports 27, escaping through the ports 15 28, while additional exhaust fluid will find an outlet through the ports 33, groove 20 and exhaust port 32. After the piston has covered port 26, any pressure in the piston chamber 6, acting against the faces 36 and 20 37 of valve, would tend to trip the valve before the piston had completed its rearward stroke, were it not for the ports 27 allowing the pressure to also come against the front face of flange 24 and overcoming 25 the pressure against the rear face 37 of the valve. Thus, ports 27 are "holding" holes to keep the valve in the rear position until the proper time for tripping the valve. Ports 33 are additional exhaust ports to allow the 30 piston to perform its full stroke. As the piston approaches the rear end of its stroke, however, the ports 27 and 33 as well as the passageway 26 will be closed. Consequently 35 the pressure will be built up behind the piston hammer until its force is sufficient, acting against the rear end of the valve to move said valve forwardly or to the position shown in Figures 2 and 4. Motive fluid will now be cut off from the passageway 31, but 40 can pass freely around the rear end of the valve and operate against the rear end of the piston, driving it forwardly. As the piston moves forward, ports 27 and 33 will be closed because of the position of the valve 45 in relation to grooves 19 and 20. As soon as the piston has uncovered groove 35, pressure is exerted against the front face 36 of valve equal to the pressure exerted against the rear face. The area of the front face 36, 50 is slightly smaller than the area of the rear face 37, so that the valve will still remain in the forward position; the pressure against the front end merely tending to almost balance the valve so that a very slight pressure 55 against the front face of the flange 24 in the groove 19 will be required to trip the valve to its rear position. The forward position of the valve will be maintained until the piston has uncovered the passageway 26, 60 whereupon live fluid will enter through said port and passageways into the groove 19 in front of the piston flange 24 and the area of said flange, together with the pressure already exerted against front face of valve, will be 65 sufficient to move the valve rearwardly, the

amount of escaping fluid through the port 28 being insufficient to prevent sufficient pressure for the purpose. The valve will thus be shifted so that the ports will again be in the position illustrated in Figure 1, 70 and a successive return movement of the piston 7 obtained.

From the foregoing, it is thought that the construction, operation and many advantages of the herein described invention will be apparent to those skilled in the art, without further description, and it will be understood that various changes in the size, shape, proportion and minor details of construction may be resorted to without departing 80 from the spirit or sacrificing any of the advantages of the invention.

What I claim is:

1. In a fluid operated tool, the combination with a cylinder member and a reciprocating piston hammer therein, of a shiftable automatic distributing valve at the rear end of the cylinder member and of tubular form to receive the rear end of the piston hammer, said valve having external fluid-actuated means by which said valve is moved and a port therethrough for supplying fluid to said means to temporarily hold the valve in a predetermined position, said valve being movable to and from said predetermined position, said port being covered and uncovered by the rear end of the piston hammer when it moves into and out of the valve, and means in addition to said port and controlled by the piston for supplying fluid to said external means to effect a movement of the valve.

2. In a fluid operated tool, the combination with a cylinder member and a reciprocating piston hammer therein, of a shiftable automatic distributing valve at the rear end of the cylinder member and of tubular form to receive the rear end of the piston hammer, said valve having an external flange, and a port therethrough for supplying fluid to one face of the flange to hold the valve in a predetermined position, means for closing the port when the valve is moved from said position, said port being covered and uncovered by the rear end of the piston hammer when it moves into and out of the valve, and means controlled by the piston for supplying fluid to the flange to operate the valve when the port is closed.

3. In a fluid operated tool, the combination with a cylinder member and a reciprocating piston hammer therein, of a valve chest having a valve chamber and an annular groove surrounding it, and a reciprocating automatic tubular distributing valve located in the chamber and having a flange located and reciprocating in the groove, said cylinder member having a passageway opening into the groove on one side of the flange and said valve having a port opening into the groove on the same side of the flange as the passageway.

way, and said piston hammer having its rear end successively movable across and closing and opening the passageway and port.

4. In a fluid operated tool, the combination with a cylinder member and a reciprocatory piston hammer therein, of a valve chest having a valve chamber and an annular groove surrounding it, and a reciprocatory automatic tubular distributing valve located 10 in the chamber and having a flange located and reciprocating in the groove, said cylinder member having a passageway opening into the groove on one side of the flange and said valve having a port opening into the 15 groove on the same side of the flange as the passageway, and said piston hammer having its rear end successively movable across and closing and opening the passageway and port, said groove also having an exhaust port 20 opening therefrom on the same side of the flange as the passageway and port and having a cross sectional area less than that of the passageway and port.
5. In a fluid operated tool, the combination 25 with a cylinder member having a piston chamber and a reciprocatory piston hammer in the piston chamber, of a valve chest at the rear end of the cylinder member having a valve chamber and an annular groove around 30 the same, a tubular automatic distributing valve in the valve chamber having an external flange operating in the groove, a passageway having an inlet end opening into the piston chamber and covered and uncovered 35 by the piston hammer, said passageway opening into the front end of the groove in advance of the flange, said valve having a port opening from its interior into the groove in advance of the flange and of less area than the 40 passageway and valve port, means controlled by the rear end of the valve for admitting motive fluid past the said rear end and into the valve against the rear end of the piston, and means controlled by said valve for directing motive fluid to the front end of the piston chamber in advance of the piston.

covering and uncovering the port, means controlled by the rear end of the valve for admitting motive fluid past said rear end and into the valve against the rear end of the piston, and means controlled by said valve 45 for directing motive fluid to the front end of the piston chamber in advance of the piston.

6. In a fluid operated tool, the combination with a cylinder member having a piston chamber and a reciprocatory piston hammer 50 in the piston chamber, of a valve chest at the rear end of the cylinder member having a valve chamber and an annular groove around the same, a tubular automatic distributing valve in the valve chamber having an external flange operating in the groove, said piston chamber having an exhaust port between its ends traversed by the piston hammer, a passageway having an inlet end opening into the piston chamber in rear of the exhaust 55 port, and covered and uncovered by the hammer, said passageway opening into the front end of the groove in advance of the flange, said valve having a port opening from its interior into the groove in advance of the flange and of less area than the 60 passageway and valve port, means controlled by the rear end of the valve for admitting motive fluid past the said rear end and into the valve against the rear end of the piston, and means controlled by said valve for directing motive fluid to the front end of the piston chamber in advance of the piston.

In testimony whereof, I affix my signature.

AUGUST H. KATTERJOHN.
